US0D1072685S

(12) **United States Design Patent** (10) **Patent No.:** **US D1,072,685 S**
(45) **Date of Patent:** **** Apr. 29, 2025**

(54) **GRILLE ASSEMBLY FOR AN AUTOMOBILE**

(71) Applicant: **Vaughn Gittin, Jr. Motorsports LLC**,
Concord, NC (US)

(72) Inventors: **Lindsay Ross**, Los Angeles, CA (US);
Eric Bauer, Los Angeles, CA (US);
Mark Wagner, Harrisburg, NC (US);
Jake Bagwell, Huntersville, NC (US)

(73) Assignee: **Vaughn Gittin, Jr. Motorsports LLC**,
Concord, NC (US)

(**) Term: **15 Years**

(21) Appl. No.: **29/967,030**

(22) Filed: **Oct. 8, 2024**

Related U.S. Application Data

(63) Continuation of application No. 29/858,346, filed on
Oct. 31, 2022.

(57) **CLAIM**

The ornamental design for a grille assembly for an automobile, as shown and described.

DESCRIPTION

FIG. 1 is a perspective view of an ornamental design for a grille assembly for an automobile, showing our new design;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The broken lines illustrate portions of the grille assembly for an automobile that form no part of the claimed design.

1 Claim, 5 Drawing Sheets
